(57) **CLAIM**

The ornamental design for a table, as shown and described.

DESCRIPTION

FIG. 1 is a perspective view of the table of the present design;

FIG. 2 is a front elevation view thereof; the rear elevation view being identical thereto;

FIG. 3 is a right side elevation view thereof; the left side elevation view being identical thereto; and,

FIG. 4 is a top plan view thereof.

The broken lines in the drawings illustrate portions of the table that form no part of the claimed design.
